UNITED STATES PATENT OFFICE.

ALFRED H. KNAPP, OF EAST PEORIA, ILLINOIS.

RAILWAY-TORPEDO.

No. 838,548.

Specification of Letters Patent.

Patented Dec. 18, 1906.

Application filed May 3, 1906. Serial No. 314,951.

To all whom it may concern:

Be it known that I, ALFRED H. KNAPP, a citizen of the United States, residing at East Peoria, in the county of Tazewell and State 5 of Illinois, have invented certain new and useful Improvements in Railway-Torpedoes; and I do hereby declare that the following is a full, clear, and exact description of the invention, which will enable others skilled in 10 the art to which it appertains to make and use the same.

This invention relates to improvements in that class of devices known as "railway-torpedoes," and has for its object to provide a 15 torpedo of paper, felt, cloth, or other material which will furnish no solid parts that might be hurled or thrown by the explosion of the torpedo.

In the accompanying drawings, which 20 illustrate my invention, Figure 1 is a top view of a railway-torpedo constructed in accordance with my invention; Fig. 2, a sectional view on the line *a a* of Fig. 1; Fig. 3, a sectional view on the line *b b* of Fig. 1; Fig. 4, 25 an outline of a wrapper which I use for covering the edges of the torpedo; and Fig. 5 is a vertical transverse sectional view of a torpedo, illustrating a modification of the torpedo shown in the preceding figures.

30 The explosive container or envelop of the torpedo consists of a waterproof cap 1, which is dome-shaped or otherwise constructed to form a receptacle for a quantity of explosive 2 and has the edge thereof flattened or flanged, as at 3, to provide a flat edge, to which the bottom 4 of the container is secured by means of a waterproof adhesive cement. The cap 1 and bottom 4 are preferably of waterproof felt, although waterproof 35 paper, cloth, or any other material which will furnish no solid fragments that might be thrown by the explosion of the explosive 2 therein may be used, and there is provided a wrapper 5, of thin waterproof material, which 40 is cemented to the under surface of the bottom 4 and has the edges turned up over and cemented to the top of the flanged edges 3 of the cap 1, so as to cover the rough edges of the said cap and the bottom 4 and insure an 45 absolutely waterproof joint.

The strap or clip for fastening the torpedo to the rail may be of lead, steel, or any suitable material that will serve the purpose and may be secured to the explosive container or 50 envelop in any manner without departing from the spirit of my invention. It is shown

herein at 6 and is secured to the bottom of the explosive-container transversely thereof by means of a strip of felt 7 or other suitable material, which is cemented to the under 60 surface of the wrapper 5, and a second wrapper 8, similar to the wrapper 5 and provided with slits 9 to accommodate the protruding ends of the strap 6, is cemented to the under surface of the strip 7, and the edges thereof 65 are turned up over and cemented to the edge of the torpedo, as shown, to give the torpedo a finished appearance.

It is apparent that the parts of the torpedo which serve to inclose the explosive must be 70 of waterproof material, and it is preferable that all parts be of such material and it is necessary that the adhesive or cement used be waterproof, so that the torpedo may stand the wet and moisture to which it is often subjected.

The modified form shown in Fig. 5 differs from the torpedo shown in the other figures in the elimination of the wrapper 5, the strap 6 being placed and secured in position immediately between the parts 4 and 7, only one 80 wrapper being used to cover the rough edges of the torpedo.

What I claim is—

1. In a torpedo of the class described, the 85 combination of two parts cemented together around their edges to form a hollow shell, a wrapper cemented to said parts and covering the joint thereof, and an explosive composition contained within said shell. 90

2. In a torpedo of the class described, the combination of a base or bottom part and cover or top part of felt, paper, cloth or other analogous material cemented together around their edges to form a hollow shell, a 95 wrapper cemented to said base or bottom part, folded over the joint of said parts and cemented to the cover or top part for covering said joint, and an explosive composition contained within said shell. 100

3. In a torpedo of the class described, the combination of a flat base or bottom part, a dome-shaped cover or top part having a flattened rim cemented to the margin of the base or bottom part to form a hollow shell, a 105 wrapper covering the joint of said parts and cemented to the contiguous portions thereof, and an explosive compound contained in said hollow shell.

4. In a torpedo of the class described, the 110 combination of two parts cemented together around their edges to form a hollow shell, an

explosive compound contained within said shell and a holding-strap fastened to said shell.

5. In a torpedo of the class described, the combination of two parts cemented together around their edges to form a hollow shell, a wrapper cemented to said parts and covering the joint thereof, an explosive composition contained within said hollow shell, and a holding-strap fastened to said shell.

6. In a torpedo of the class described, the combination of a base or bottom part and cover or top part of felt, paper, cloth or other analogous material cemented together around their edges to form a hollow shell, a wrapper cemented to said base or bottom part, folded over the joint of said parts and cemented to the cover or top part for covering said joint, an explosive composition contained within said shell, and a holding-strap secured to the under surface of said shell.

7. In a torpedo of the class described, the combination of two parts cemented together around their edges to form a hollow shell, an explosive composition contained within said shell, a holding-strap lying in contact with said shell and secured thereon by means of an overlying strip of material cemented to the shell.

30 8. In a torpedo of the class described, the combination of a base or bottom part and cover or top part of felt, paper, cloth or other analogous material cemented together around their edges to form a hollow shell, a wrapper cemented to said base or bottom part, folded over the joint of said parts and cemented to the cover or top part for covering said joint, an explosive composition contained within said shell, a strap lying in contact with the under surface of the said shell, and an overlying strip of felt, paper, cloth or other material cemented to said hollow shell for securing the strap thereon.

45 9. In a torpedo of the class described, the combination of a flat base or bottom part, a dome-shaped cover or top part, having a flattened rim which is cemented to the margin of the base or bottom part to form a hollow shell, a wrapper cemented to the base or bottom part, folded over the joint of said parts and cemented to the cover or top part, an explosive contained within said shell, a holding-

strap lying against the bottom of said hollow shell, a strip of material overlying said strap and cemented to the hollow shell for securing the strap thereon.

55 10. In a torpedo of the class described, the combination of a base or bottom part and a cover or top part cemented together around their edges to form a hollow shell, an explosive composition contained within said shell, a strap secured to said shell, and a wrapper overlying the portion of the strap adjacent the shell and covering and cemented over the joint of the top and bottom parts of the shell.

60 11. In a torpedo of the class described, the combination of a plurality of parts provided with matching overlapping edges, an adhesive cement intermediate of the said matching overlapping edges for combining the parts to form a hollow shell, an explosive composition contained within said shell and a holding-strap secured to said shell.

65 12. In a torpedo of the class described, the combination of a plurality of parts joined together to form a hollow shell, an explosive composition contained within said shell, and a wrapper folded over the joint of the said parts and cemented to the contiguous portions thereof for covering the joint.

70 13. In a torpedo of the class described, the combination of a plurality of parts provided with matching overlapping edges, an adhesive cement intermediate of the said matching overlapping edges for combining the parts to form a hollow shell, an explosive composition contained within said shell, and a wrapper folded over the juncture of the parts and cemented to the contiguous portions of said parts.

75 14. In a torpedo of the class described, the combination of a plurality of parts joined together to form a hollow shell, an explosive composition contained within said shell, a wrapper folded over the joint of said parts and cemented to the contiguous portions thereof and a holding-strap secured to said shell.

80 In testimony whereof I have affixed my signature in presence of two witnesses.

85 ALFRED H. KNAPP.
